F. CONILL.

MASSAGE IMPLEMENT.

APPLICATION FILED MAR. 21, 1917.

1,349,495.

Patented Aug. 10, 1920.

UNITED STATES PATENT OFFICE.

FERNAN CONILL, OF NEW YORK, N. Y.

MASSAGE IMPLEMENT.

1,349,495.

Specification of Letters Patent. Patented Aug. 10, 1920.

Application filed March 21, 1917. Serial No. 156,328.

To all whom it may concern:

Be it known that I, FERNAN CONILL, a citizen of the Republic of Cuba, residing at New York, in the county of New York and State of New York, have invented certain new and useful Improvements in Massage Implements; and I do hereby declare the following to be a full, clear, and exact description of the invention, such as will enable others skilled in the art to which it appertains to make and use the same.

This invention relates to new and useful improvements in mounts capable of supporting safety razors or massage implements, and the primary object of the invention resides in the provision of a device as specified having a sliding working element which moves longitudinally of the guard.

Another object of the invention is to provide a novel means for holding the cap piece in place by which the working element is slidably supported in position.

A further object of the invention is to provide a device which is operated by means of a flexible shaft thus enabling the driving mechanism to be positioned at any desired point.

A further object of the invention is to provide a device which may be readily detached from the flexible shaft.

With these and other objects in view, the invention consists in the novel combination and arrangement of parts which will be fully set forth in the following specification and accompanying drawings, in which:

Figure 1 is a longitudinal sectional view through the improved mount.

Fig. 2 is a longitudinal sectional view through the head portion of the mount showing a slightly modified construction.

Fig. 3 is a detail elevation of the massage blade or plate shown in position in Figs. 1 and 2.

Referring to the drawing, the numeral 1 designates the handle of the support provided with a longitudinal bore 2 in which the shaft is rotated. A hollow boss 3 is formed at one end of the handle and forms the support on which the head of the razor is secured. The opposite end of the handle is provided with an enlarged external bore 4 into which the end of the flexible shaft is secured by means of a set screw 5. A drive shaft 6 extends through the bore 2 and is provided at one end with the rectangular

portion 7 to which the flexible shaft is connected, while the opposite end of the drive shaft is formed with an eccentric 8 as clearly shown in the drawing.

The guard head is designated by the numeral 9 and is provided with a central aperture for the reception of the boss 3 to which the head is secured. Rotatably mounted between the head and shoulder 65 formed by the boss 3 is a ring 10, provided with diametrically arranged spring arms 11, the ends of which are adapted to engage the studs of the cap piece to hold the cap piece in place. Suitable pins 12 are carried by 70 the arms 11 and engage in the recesses 13 formed in the head in such position as to hold the arms and ring against accidental movement. Formed in the guard head 9 and in longitudinal alinement with the central opening are the spaced openings 13' through which the studs of the cap piece 15 extend. A central recess 14 is formed in the outer face of the head to accommodate 75 the flange of the bushing on which the eccentric runs.

The cap piece 15 is provided adjacent opposite ends with threaded openings for the reception of the threaded terminals 16 of the studs 17. Formed on the studs at 80 the point where the threaded terminals join the same, are flanges 18 which form guides on which the blade slides. A central aperture is formed in the plate 15 for the reception of the outer end of the shaft 90 6 and formed in the inner face of the plate is a recess 19 in which the head of the bushing of the blade is slidable as clearly illustrated in Fig. 2. The studs 17 hereinbefore referred to are arranged in such position 95 as to be received in the openings 13' and are formed with notches 20 for the reception of the arms 11 when the blade is in place and with notches 21 for the reception of the arms when the massage plate is in place.

It will thus be apparent that in assembling the device the blade 25 is placed in position on the flanges 18 of the studs with said flanges received in the longitudinal slots 26 formed in said blade, after which 105 the studs 17 are passed through the openings 13' so that the eccentric 8 on the drive shaft 6 will be received within the transverse slot 28 in the bushing 27, the head of which is disposed on the outer side of the 110 blade while the opposite end is flanged over the blade in order to secure the bushing

in place. After the whole has been assembled in the manner previously described, the arms 11 are turned so that their ends will enter the notches 20 in the studs 17 and thereby securely lock the parts against accidental movement. The blade extends beyond the ends of the head and at one end of the plate is a weight 29 while the opposite end has projecting therefrom a stud 30 supporting at its end a suitable massage cup 31 which may be formed of any desirable material but is preferably of a soft rubber or the like.

It will be apparent from the foregoing, that in use the rotation of the shaft 6 will cause the massage plate and cup 31 to vibrate producing the advantages to be had thereby without the necessity of providing an expensive and complicated mechanism.

In order to drive the device, the flexible shaft designated generically by the numeral 32 is provided which shaft consists of an outer coil of wire 33 and an inner coil of wire 34. These wires are preferably piano wire, or similar highly tempered wire and secured to the outer coil 33 is a socket 35, the end of which enters the enlarged bore 4 and is secured in place by means of the set screw 5. The end of the inner coil is connected to a socket 36 which is provided with a central rectangular aperture for the reception of the rectangular extension 7 on the shaft 6. It will thus be seen that when the inner coil is rotated the shaft 6 will be driven.

While in the foregoing there has been shown and described the preferred embodiment of this invention, it is to be under-

stood that such changes may be made in the combination and arrangement of parts 40 as will fall within the spirit and scope of the appended claim.

What is claimed is:—

In a device of the character described, an axially bored handle, a head secured on 45 one end of said handle and provided with spaced apertures, a cap piece, studs secured in said cap piece and projecting through the apertures of said head, the studs being provided with notches beyond the head and 50 having guide flanges adjacent the inner face of the cap piece, a shaft rotatably mounted through the handle and provided on its inner end with an eccentric, a plate reciprocable between the head and cap piece 55 provided with slots for reception of the guide flanges and with a central opening receiving said eccentric for reciprocating the plate when the shaft is rotated, and resilient locking arms turnable about the handle 60 into engagement with the notches of said studs, said arms being adapted to be placed under tension when in locking position so as to force the cap piece toward the head 65 for preventing looseness of said plate while permitting reciprocation thereof, said plate being provided with a massage member at one end and a weight member at its other end.

In testimony whereof I affix my signature 70 in presence of two witnesses.

FERNAN CONILL.
